UNITED STATES PATENT OFFICE.

MALCOLM L. COSSITT, OF OAKLAND, CALIFORNIA, ASSIGNOR TO MANIFOLD IMPRESSIONS CORPORATION, OF CARSON CITY, NEVADA, A CORPORATION OF NEVADA.

MANIFOLDING PLATEN FOR TYPEWRITERS.

Application filed August 12, 1922. Serial No. 581,478.

To all whom it may concern:

Be it known that I, MALCOLM L. COSSITT, a citizen of the United States, residing at the city of Oakland, county of Alameda, and 5 State of California, have invented certain new and useful Improvements in Manifolding Platens for Typewriters, of which the following is a specification.

My invention relates to the art of producing 10 copies of originals by the employment of manifold impression members. It is generally adapted for devices and machines employing an impression tablet, but especially for typewriting and type impression machines in which the tablet employed is the common, rotatable, cylindrical platen.

The object of my invention is to provide a manifolding device comprising a platen member, a manifolding member and operating mechanism all incorporated in such intimate relation as to form a single unitary, self contained structure, equally adapted for incorporation in the original manufacture of machines and for substitution for the usual 25 platens of existing machines.

To this end my invention consists in the novel manifolding platen which I shall now fully describe by reference to the accompanying drawings, in which—

30 Fig. 1 is a longitudinal section, broken, of my manifolding platen.

Fig. 2 is a section on the line 2—2 of Fig. 1.

Fig. 3 is a section on the line 3—3 of 35 Fig. 1.

Fig. 4 is a section on the line 4—4 of Fig. 1.

Fig. 5 is a section on the line 5—5 of Fig. 1.

40 Fig. 6 is a section on the line 6—6 of Fig. 1.

Fig. 7 is a section on the line 7—7 of Fig. 1, one of the manifolding members being shown in functional position.

45 Fig. 8 is a perspective view showing the pivotal and radially slidable association of the carrying arms of the manifolding members and the sleeves which connect a pair of arms for unitary movement.

50 Fig. 9 is a perspective view showing a modification with respect to the mounting of the manifolding member for swinging and radially sliding movement.

The platen member proper comprises a peripheral portion 1 with covering 2, and 55 ends 3. It is rotatably mounted, by means of its ends, upon a hollow bearing member 4 which extends longitudinally through it and which carries at each end a housing 5, adjacent to but independent of the platen 60 member ends.

6 is a rotatable shaft lying in the axis of the platen member, the housing 5, and their connecting bearing member 4. One end of this shaft carries a knob 7 for turning it.

Upon shaft 6 are one or more sleeves, here shown as three—Fig. 1. These sleeves are nested and are mounted for independent rotation about the shaft 6 as a common axis. 70 The outermost sleeve is designated by 8, the next by 8' and the innermost by 8''. The ends of these sleeves project into the respective housings 5 to successive distances, the outermost extending therein to the shortest distance and the innermost to the longest— 75 as seen in Fig. 1. Fitted upon each end of the sleeves are the respective carrying arms 9, 9' and 9''. The connection between the arms and the sleeves is one which adapts said arms by swinging movement to rotate the sleeves, and during their swinging movement to slide radially with respect to the sleeves. Such connection is herein shown, 80 particularly in Figs. 7 and 8, as comprising a bifurcated inner end 10 of the arm, slidably forked upon the flattened sides 11 of the sleeve extremity. The arms 9, 9' and 9'' are conveniently spaced by washers 12, Fig. 1, at their inner ends, and thence said arms extend in parallel spaced relation radially within the housings 5 and out through the peripheral wall of the housings in elongated slots 13 in said wall, as seen in Fig. 1.

85 Between the extremities of each pair of arms is carried the manifolding members 14, 14' and 14'' respectively, indicated by dotted lines in Fig. 1, said members bearing a copying medium adapting them for manifolding.

90 It will now be seen that if one of the arms be swung in an arcuate path, it will turn the sleeve to which it is fitted; and the corresponding arm at the other end of the sleeve will thereby be moved in unison with the first arm. Moreover, by reason of the radially slidable fitting of the arms on the 100 105

sleeve, it is possible under the influence of suitable guides to distort the arcuate path to one eccentric to its axis. Such a guide is provided by an eccentric slot 15—Figs. 3 and 6, in the wall of the housings 5, in which slots the studs 16 projecting laterally from the arms play. The eccentricity of the guide slot 15 is such that when the studs 16 are in the outer end of the slots 10 the arms are projected to their limit beyond their housings 5, Fig. 1, and as the studs move forward and down in the slot 15, the arms are retracted to their inner limit, as seen by the depressed arm in Fig. 7.

15 The effect of this is to elevate the manifolding members when out of use, as seen in Fig. 1, sufficiently far above the platen, to get them well out of the way; also to enable the tops of the record sheets to be conveniently handled to receive the manifolding members between them when said members are depressed; also to conveniently renew said members, since the arms project far enough to enable the members of a pair to be pressed towards each other, the arms being resilient laterally, as is known in the art, and thus permit the manifolding member to be readily attached, and held under tension by the backward spring of 25 the arms, the tension effect being heightened as the arms move down and retract within the peripheral slots of the housings; and, also finally, a matter that is very important, to provide for a movement of said arms 30 about the axis of the platen which will result in the final depressed functional position of the manifolding members in the line of type impact as close to the platen as may be required, as seen in Fig. 7. Thus both 35 elevation of the manifolding members well and conveniently beyond the surface of the platen, and their retraction inwardly close to said surface are effected in a single continuous eccentric path, about the axis of the 40 platen.

45 In order to operate the arms, and, where a plurality of pairs of arms, as herein shown, are present, to operate them selectively and successively, there is the following mechanism.

50 Pivotally mounted upon the central shaft 6, within the housing 5 at the right hand end, are the three levers 17, 17' and 17''—Fig. 1. The upper end of the first lever 17 is forked at 18 over the stud 16 of the first arm 9, while the upper ends of the other two levers lie behind the studs 16 of the other arms respectively, as seen in Fig. 6.

55 The lower ends of the levers are provided 60 with the laterally projecting pins 19, 19' and 19'' respectively, which play in slots 20, 20' and 20''—Fig. 5 respectively, in the walls of the housing 5, said slots being concentric with the axis of movement of the pins. Figs. 65 4 and 5.

It will now be seen that if the pin 19 be caused to travel, it will turn its lever 17, about the shaft 6, and the upper end of the lever engaging the stud 16 of the foremost arm 9, will swing said arm. So, too, will 70 the other arms 9' and 9'' be swung, if the levers 17' and 17'' be operated.

75 Mounted rotatably upon the shaft 6 is a sleeve 21, Fig. 1, having a knob 22 for turning it. The inner end of the sleeve carries a crank 23, as seen in Fig. 5, to which is pivoted a pawl 24, controlled by a spring 25, tending to throw the pawl outwardly. When the pawl is in its closest-in position, that is, nearest the sleeve 21, it lies in position to engage the pin 19 of the lever 17. In its next outer position it engages the pin 19' of the lever 17' and in its outmost position it engages the pin 17'' of the lever 17''. A stop stud 26 on the pawl, coacts with a fixed 80 cam 27 on the inner wall of the housing 5 to control these positions.

85 Upon the crank 23 is a return arm 28—Fig. 5, which, when the rotation of the sleeve 21 is reversed, is adapted to contact 90 with the innermost pin 19, and by moving back the lever 17 of said pin, will through the forked end 18 of said lever move the stud 16 of the first arm 9; and as said arm is the innermost of the arm series, and the arm 95 studs 16 are nested in the arms as shown in Fig. 7, all the levers and arms will be returned, and moreover in this return movement the stop stud 26 of the selective pawl 24, engaging the cam 27, will restore the 100 pawl to its normal close-in position. By these means the manifolding members may be selectively and successively moved to functional position and all thrown up again together. This selective mechanism being 105 substantially the same as that I have heretofore disclosed and claimed in a previous application—Serial Number 566717, filed June 8, 1922, I have not deemed it necessary 110 to explain it in greater detail, but I 110 illustrate it herein merely to show a suitable means for selectively operating a plurality of manifolding members.

115 In order to yieldingly hold the arms at their limits of movement, against inadvertent or accidental displacement, I attach to the outer surface of the housing 5, spring keepers 29—Figs. 1 and 4, which act upon the projecting ends of the lever pins 19, 19' and 19''. 120

125 As my manifolding platen is to be employed, instead of the ordinary platen, in the original manufacture of machines, and is to be substituted for the common platen in existing machines, provision must be made for the usual functions of such platens. One of these functions is its capacity for rotation, freely for variable spacing, and under definite control for line spacing. Obviously, as thus far described, the presence 130

of the manifolding elements of the structure running through the platen, prevent any direct mounting or rotative connection between the platen member and the shaft 6, so that, in the absence of such connection the rotation of said shaft would not effect the rotation of the platen.

To have this effect, however, I provide the following mechanism and its controls. Referring now to Fig. 1, 30 is a bracket adapted to be fixed by a set screw 31 to a convenient projection, not shown, upon the left hand end of the platen carriage of the machine. This bracket has a circular flange 32 upon the periphery of which is fitted for rotation the line spacing ratchet 33 which is adapted to be actuated and definitely controlled by the usual mechanisms found on typewriters, but not herein shown. The ratchet 33 is provided with an offset internal ring of clutch teeth 34, Figs. 1 and 2.

Feathered upon the projecting left hand end of the shaft 6, is a slidable clutch member 35, adapted to be held either out or in by a latch 36 controlled by a spring 37 and engaging a pair of notches 38 in the shaft. A knob 39 is fixed to the clutch member 35 to enable it to be conveniently drawn out or forced in.

30 The member 35 effects its clutching function by means of an external tooth ring 40, Figs. 1 and 2, which is adapted to slide into the tooth ring 34 of the ratchet 33 or to be withdrawn therefrom, thereby rotatively connecting or disconnecting the ratchet with the shaft 6. When, therefore, the clutch rings are in engagement, the rotation of the shaft 6 will rotate the ratchet, and when the rings are disengaged the ratchet is free.

40 41 is a short countershaft journaled for rotation in the flange 32 of the fixed bracket 30.

The outer end of this shaft has fitted upon it by a feather, a slidable pinion 42, provided with side flanges or shrouds 43, Fig. 1. An internal gear 44 on the clutch member 35 enters between the shrouds of the pinion 42 and engages the pinion. Figs. 1 and 2.

50 The other end of the countershaft 41 passes through the housing 5 and enters the platen, Fig. 1. This end carries a pinion 45 which engages an internal gear 46 of the platen. When the parts are in the position shown in Fig. 1, the rotation of the shaft 6 by means of its turning knob 7 at the right hand end, will turn the clutch member 35 at the other end, and since this member has its internal gear 44 engaging the pinion 42, the countershaft 41 will be rotated. Through the rotation of the shaft 41, the pinion 45 on its other end, engaging the internal gear 46 of the platen, the platen will be rotated. As the clutch member is engaging the ratchet 33 the latter will also be

rotated, and as the ratchet is under the exterior control of the usual devices on the machine, the rotation of the platen member will be definite for line spacing. The same results will follow the rotation of the shaft 6 by turning the left hand knob 39; and also the same results will follow the direct rotation of the ratchet by the customary line spacing lever. But if the rotation of the platen member be required for variable spacing, all that is necessary is to pull back the clutch member 35 to its outer position. This has the effect of disengaging the ratchet, so that the definite external control of the ratchet being dispensed with, the platen may be turned freely to any extent desired, since the gear 44 of the clutch member when the said member is slid back, still remains in engagement with the pinion 42 of the countershaft 41, due to the sliding back of the pinion also. Nor, in this case, will the line spacing lever acting on the ratchet have any effect on the platen member, because the ratchet is then loose.

In order to vary the width relation of the manifolding members to the line of type impact upon the line spacing movement of the platen, so that said members may present different portions of their width surface to the type blow and thereby prolong their life, provision is made as follows:

The countershaft 41 passes through the walls of the housing 5 in elongated arcuate slots 47, as seen in Fig. 3, and in one of these slots, said shaft carries a cam 48, which, when the shaft is rotated causes a slight rotation of the housing, and this movement of the latter causes the manifolding members, when in functional position to vary their width relation to the line of type impact.

It will be noted that the sleeves 8, 8' and 8'', have merely the function of connecting the paired arms, to enable them to move in unison when the operating mechanism is applied at one end. This is now known in the art, but, it is obvious, however, that the equally known expedient of applying the arm operating selective pawl mechanism to each arm of an otherwise unconnected pair, is also available.

In the form of the device thus far described, the radially slidable movement of the manifolding members is effected by the forking of the arms over their sleeves. But in Fig. 9, I show a modification in this regard. In this figure the arm is not slidable upon its sleeve but is fast thereon. The arm is however longitudinally slotted at 49, and in this slot is mounted a slide 50 which carries the manifolding member, said slide having the laterally projecting stud 51 which is to play in the eccentric guide slot 52 of the housing. In this modification, the arms proper do not slide radially, but the

4
manifolding members describe their eccentric path due to the radial movement of their carrying slides 50.

A brief résumé of the operation of the manifolding platen herein described may be of service.

When the manifolding members are out of use, they are well elevated above the platen, as seen in Fig. 1, and the record sheets may be entered and manipulated without interference. If a single duplicate only is wanted, the knob 22 is turned, and the selective pawl 24 brings forward the pair of arms 9 of the first manifolding member 14. In moving forward, said member describes a path eccentric to the axis of platen, the path closing in on the downward course, until the manifolding member comes directly and squarely into position close to the platen, in the line of type impact, as seen in Fig. 7.

If more manifolding members are required, they are successively brought forward to position.

In the return movement, they gradually diverge from the platen to their normal elevated position. Both in use and out of use, the manifolding elements and structures of the device present no interference to the ordinary and necessary movements and uses of the platen.

I claim:—

1. A manifolding platen comprising a platen member; a member bearing a copying medium; a pair of arms for carrying said last named member, pivotally mounted to swing about centers in a line passing longitudinally through the platen member; and means operating through said platen member for swinging the arms in unison.

2. A manifolding platen comprising a platen member; a member bearing a copying medium; a pair of arms for carrying said last named member, pivotally mounted to swing about the axis of the platen member; and means operating through said platen member for swinging the arms in unison.

3. A manifolding platen comprising a platen member; a member bearing a copying medium; a pair of arms for carrying said last named member, pivotally mounted to swing about the axis of the platen member; and means operating through said platen member and about the axis thereof, for swinging the arms in unison.

4. A manifolding platen comprising a platen member; a manifolding member; a pair of arms for carrying said manifolding member; and a rotatable sleeve passing longitudinally through the platen member and carrying said arms for unitary movement.

5. A manifolding platen comprising a platen member; a manifolding member; a

pair of arms for carrying said manifolding member; and a rotatable sleeve passing longitudinally through the platen member in the axis thereof, and carrying said arms for unitary movement.

70

6. A manifolding platen comprising a platen member; and a member bearing a copying medium and adapted to swing about an axis passing longitudinally through the platen member.

75

7. A manifolding platen comprising a platen member; and a member bearing a copying medium and adapted to swing about the axis of the platen member.

80

8. A manifolding platen comprising a platen member; and a manifolding member adapted to swing in a path eccentric to the axis of said member, about an axis passing longitudinally through said platen member.

85

9. A manifolding platen comprising a platen member; and a manifolding member adapted to swing about the axis of the platen member in a path eccentric to said axis.

90

10. A manifolding platen comprising a platen member; a manifolding member adapted to swing about an axis passing longitudinally through the platen member; and means operating simultaneously with said swinging movement to render its path eccentric to the platen axis.

95

11. A manifolding platen comprising a platen member; a manifolding member adapted to swing about the axis of the platen member; and means operating simultaneously with said swinging movement of the manifolding member to render its path eccentric to said axis.

100

12. A manifolding platen comprising a platen member; a manifolding member; means for carrying the manifolding member; and means for mounting said carrying means for simultaneous pivotal movement about an axis passing through the platen member and for radially sliding movement.

105

13. A manifolding platen comprising a platen member; a manifolding member; means for carrying the manifolding member; and means for mounting said carrying means for simultaneous pivotal movement about and radially sliding movement relatively to the platen member axis.

110

14. A manifolding platen comprising a platen member; a manifolding member; means for carrying the manifolding member; means for mounting said carrying means for pivotal movement about and radially sliding movement relatively to the platen member axis; and means operating simultaneously with the pivotal movement of the carrying means for effecting its radially sliding movement.

115

15. A manifolding platen comprising a platen member; a manifolding member; a pair of spaced arms for carrying said mani-

120

folding member; and means for mounting said arms pivotally and radially slidably about the platen member axis.

16. A manifolding platen comprising a platen member; a manifolding member; a pair of spaced arms for carrying said manifolding member; means for mounting said arms pivotally and radially slidable about the platen member axis; and means operating simultaneously with the pivotal movement of said arms to effect their radially sliding movement. 70

17. A manifolding platen comprising a platen member; a manifolding member; and a pair of spaced arms for carrying said manifolding member, said arms being slotted over the axis of the platen member for pivotal and radially slidable movement. 75

18. A manifolding platen comprising a platen member; a manifolding member; a pair of spaced arms for carrying said manifolding member; said arms being slotted over the axis of the platen member for pivotal and radially slidable movement; and guides for effecting the sliding movement of the arms while executing their pivotal movement. 80

19. A manifolding platen comprising a platen member; a rotatable shaft passing through the axis of the platen member; means associated with said shaft and platen member for effecting a variable line-spacing movement of the platen member; means associated with said shaft for effecting a definite line spacing movement of said platen member; means for throwing said definite line-spacing means into and out of function; a manifolding member; a pair of carrying members for said manifolding member; means for swinging movement about and radially sliding movement relatively to said shaft, said carrying members being adjacent the ends of the platen member; means passing through the platen member, connecting said carrying members for unitary movement; means for swinging said carrying members about said shaft; and means for directing them while executing their swinging movement into a path eccentric to 100 said shaft. 105

20. A manifolding platen comprising a platen member; a rotatable shaft passing through the axis of said platen member; means associated with said shaft and platen member for effecting a variable line-spacing movement of the platen member; means associated with said shaft for effecting a definite line-spacing movement of said platen member; means for throwing said definite line-spacing means into and out of function; a manifolding member; a pair of carrying members for said manifolding member, mounted for swinging movement about and radially sliding movement relatively to said shaft, one of said carrying members being adjacent each end of the platen member; and means operating longitudinally through said platen member for moving said carrying members in unison. 115

21. A manifolding platen comprising a

platen member; a rotatable shaft passing through the axis of said member; means associated with said shaft and platen member

for effecting a variable line-spacing movement of the platen member; means associated with said shaft for effecting a definite line-spacing movement of said platen member; means for throwing said definite line-spacing means into and out of function; a manifolding member; a pair of carrying members for said manifolding member, mounted for swinging movement about and radially sliding movement relatively to said shaft, one of said carrying members being adjacent each end of the platen member; means passing through the platen member for connecting said carrying members for unitary movement; a rotatable sleeve mounted on said shaft and means actuated by the rotation of said sleeve for operating said carrying means to move the manifolding member into and out of functional position in the line of type impact. 85

22. A manifolding platen comprising a platen member; a rotatable shaft passing through the axis of said platen member; means associated with said shaft and platen member for effecting a variable line-spacing movement of the platen member; means associated with said shaft for effecting a definite line-spacing movement of said platen member; means for throwing said definite line-spacing means into and out of function; a manifolding member; a pair of carrying members for said manifolding member, mounted for swinging movement about and radially sliding movement relatively to said shaft, said carrying members being adjacent the ends of the platen member; means passing through the platen member, connecting said carrying members for unitary movement; means for swinging said carrying members about said shaft; and means for directing them while executing their swinging movement into a path eccentric to 110 said shaft. 100

23. A manifolding platen comprising a platen member; a rotatable shaft passing through the axis of said platen member; means associated with said shaft and platen member for effecting a variable line-spacing movement of the platen member; means associated with said shaft for effecting a definite line-spacing movement of said platen member; means for throwing said definite line-spacing means into and out of function; a manifolding member; a pair of carrying members for said manifolding member, mounted for swinging movement about and radially sliding movement relatively to said shaft, said carrying members being adjacent the ends of the platen member; means passing through the platen member, connecting said carrying members for unitary movement; means for swinging said carrying members 115

members about said shaft; and means for directing them while executing their swinging movement into a path eccentric to said shaft, consisting of studs on the carrying members and eccentrically slotted members in which said studs play.

24. A manifolding platen comprising a platen member; a rotatable shaft passing through the axis of said platen member; means associated with one end of said shaft and said platen member for effecting a variable line-spacing movement of the platen member; means associated with said shaft for effecting a definite line-spacing movement of said platen member; means for throwing said definite line-spacing means into and out of function; a sleeve rotatably mounted upon said shaft within and projecting beyond the ends of the platen member; a pair of arms mounted upon the ends of said sleeve for rotation therewith and radially slidably movement thereon, one arm adjacent each end of the platen member; a manifolding member carried by said pair of arms; a second sleeve rotatably mounted upon one end of the axis shaft, means actuated by the rotation of said second sleeve for operating said arms to move the manifolding member into and out of functional position in the line of type impact, and means for directing the arms in their swinging movement into a path eccentric to the axis shaft consisting of studs on the arms and eccentrically slotted members in which said studs play.

25. A manifolding platen comprising a platen member; a rotatable shaft passing through the axis of said platen member; means associated with one end of said shaft and said platen member for effecting a variable line-spacing movement of the platen member; means associated with said shaft for effecting a definite line-spacing movement of said platen member; means for throwing said definite line-spacing means into and out of function; a sleeve rotatably mounted upon said shaft within and projecting beyond the ends of the platen member; a pair of arms mounted upon the ends of said sleeve for rotation therewith and radially slidably movement thereon, one arm adjacent each end of the platen member; a manifolding member carried by said pair of arms; a second sleeve rotatably mounted upon one end of the axis shaft; and means actuated by the rotation of said second sleeve for operating said arms to move the manifolding member into and out of functional position in the line of type impact.

26. A manifolding platen comprising a platen member; a rotatable shaft passing through the axis of said platen member; means associated with one end of said shaft and said platen member for effecting a variable line-spacing movement of the platen member; means associated with said shaft for effecting a definite line-spacing movement of said platen member; means for throwing said definite line-spacing means into and out of function; a sleeve rotatably mounted upon said shaft within and projecting beyond the ends of the platen member; a pair of arms mounted upon the ends of said sleeve, for rotation therewith and radially slidably movement thereon, one arm adjacent each end of the platen member; a manifolding member carried by said pair of arms; a second sleeve rotatably mounted upon one end of the axis shaft, means actuated by the rotation of said second sleeve for operating said arms to move the manifolding member into and out of functional position in the line of type impact, and means for directing the arms in their swinging movement into a path eccentric to the axis shaft.

27. A manifolding platen comprising a platen member; a peripherally slotted housing adjacent to and independent of the ends of the platen member; a hollow member in the axis of the platen member, connecting said housings; a shaft passing longitudinally through said hollow member; a pair of arms one in each housing projecting through and playing in the peripheral slots thereof, the inner ends of the arms within the housings being pivotally and radially slidably mounted about the shaft; and a manifolding member carried by and between the outer ends of said pair of arms.

28. A manifolding platen comprising a platen member; a peripherally slotted housing adjacent to and independent of the ends of the platen member; a hollow member in the axis of the platen member, connecting said housings; a shaft passing longitudinally through said hollow member; a pair of arms one in each housing projecting through and playing in the peripheral slots thereof, the inner ends of the arms within the housings being pivotally and radially slidably mounted about the shaft; a manifolding member carried by and between the outer ends of said pair of arms, a sleeve rotatably mounted on the shaft and coacting devices on said sleeve and arms to swing the arms by the rotation of the sleeve.

29. A manifolding platen comprising a platen member; a peripherally slotted housing adjacent to and independent of the ends of the platen member; a hollow member in the axis of the platen member, connecting said housings; a shaft passing longitudinally through said hollow member; a pair of arms one in each housing projecting through and playing in the peripheral slots thereof, the inner ends of the arms within the housings being pivotally and radially slidably mounted about the shaft; a manifolding member carried by and between the outer ends of said pair of arms, a

sleeve rotatably mounted on the shaft, co-acting devices on said sleeve and arms to swing the arms by the rotation of the sleeve, studs on the arms and slots in the housing 5 wall in which the studs play said slots being eccentric to said shaft.

30. A manifolding platen comprising a platen member; a peripherally slotted housing adjacent to and independent of the ends 10 of the platen member; a hollow member in the axis of the platen member connecting said housings; a shaft passing longitudinally through said hollow member; a pair of arms one in each housing projecting 15 through and playing in the peripheral slots thereof, the inner ends of the arms within the housings being pivotally and radially slidably mounted about the shaft; a manifolding member carried by and between the 20 outer ends of said pair of arms; laterally projecting studs on the arms playing in slots in the side wall of the housing eccentric to the shaft; levers in the housing pivoted on the shaft with one end in engagement 25 with the studs of the arms; pins on the other ends of the levers playing in slots in the side wall of the housing concentric with the shaft; a sleeve rotatably mounted on the shaft; and means carried by the 30 sleeve and engaging the pins of the levers, to operate them.

31. A manifolding platen comprising a platen member; a peripherally slotted housing adjacent to and independent of the 35 ends of the platen member; a hollow member in the axis of the platen member connecting said housings; a shaft passing longitudinally through said hollow member; a pair of arms one in each housing projecting 40 through and playing in the peripheral slots thereof, the inner ends of the arms within the housings being pivotally and radially slidably mounted about the shaft; a manifolding member carried by and between the 45 outer ends of said pair of arms; laterally projecting studs on the arms playing in slots in the side wall of the housing eccentric to the shaft; levers in the housing pivoted on the shaft with one end in engagement 50 with the studs of the arms; pins on the other ends of the levers playing in slots in the side wall of the housing concentric with the shaft; a sleeve rotatably mounted on the shaft; means carried by the sleeve and 55 engaging the pins of the levers, to operate them, and springs on the side wall of the housing to yieldably hold the pins of the levers at their limits of movement.

32. A manifolding platen comprising a 60 platen member; a peripherally slotted housing adjacent to and independent of the ends of the platen member; a hollow member in the axis of the platen member connecting said housings; a shaft passing longitudinal- 65 ly through said hollow member; a plurality

of independently rotatable nested sleeves carried by said shaft and projecting into the housing at each end; a plurality of arms mounted on the projecting ends of the sleeves for rotation therewith and for radially slidable movement thereon, said arms projecting through and playing in the peripheral slots of the housings; manifolding members carried by the outer ends of the arms; a rotative member carried by the 70 shaft; and coacting devices between said rotative member and the arms to operate said arms, selectively and successively.

33. A manifolding platen comprising a platen member; a peripherally slotted housing adjacent to and independent of the end of the platen member; a hollow member in the axis of the platen member connecting said housings; a shaft passing longitudinally through said hollow member; a plurality 80 of independently rotatable nested sleeves carried by said shaft and projecting into the housing at each end; a plurality of arms mounted on the projecting ends of the sleeves for rotation therewith and for radially slidable movement thereon, said arms projecting through and playing in the peripheral slots of the housings; manifolding members carried by the outer ends of the arms; a rotative member carried by the 85 shaft; and coacting devices between said rotative member and the arms to operate said arms, selectively and successively consisting of a plurality of levers pivotally mounted on the shaft; studs on the arms with which the levers engage; pins on the levers; and a selective pawl carried by the rotative member for engaging said pins.

34. A manifolding platen comprising a platen member; a peripherally slotted housing adjacent to and independent of the ends of the platen members; a hollow member in the axis of the platen member connecting said housings; a shaft passing longitudinally through said hollow member; a plurality 100 of independently rotatable nested sleeves carried by said shaft and projecting into the housing at each end; a plurality of arms mounted on the projecting ends of the sleeves for rotation therewith and for radially slidable movement thereon, said arms projecting through and playing in the peripheral slots of the housings; manifolding members carried by the outer ends of the arms; a rotative member carried by the 105 shaft; and coacting devices between said rotative member and the arms to operate said arms, selectively and successively consisting of a plurality of levers pivotally mounted on the shaft; studs on the arms with which the levers engage; said studs playing in slots in the side wall of the housing, eccentric to the shaft, pins on the levers; and a selective pawl carried by the rotative member for engaging said pins.

35. A manifolding platen comprising a platen member; a rotatable shaft passing through the axis of said platen member and about which said platen member is independently mounted; a pair of arms pivotally and radially slidably mounted about said shaft, one arm adjacent each end of the platen member; means passing through the platen member for connecting the arms at each end; means for operating said arms; a manifolding member carried by the arms; a counter shaft passing into one end of the platen member and geared thereto for rotating said member; and means rotatively connecting the axis shaft and said counter shaft. 45
36. A manifolding platen comprising a platen member; a rotatable shaft passing through the axis of said platen member and about which said platen member is independently mounted; a pair of arms pivotally and radially slidably mounted about said shaft, one arm adjacent each end of the platen member; means passing through the platen member for connecting the arms at each end; means for operating said arms; a manifolding member carried by the arms; a counter shaft passing into one end of the platen member and geared thereto for rotating said member; means rotatively connecting the axis shaft and said counter shaft; a rotatively mounted line spacing ratchet; and a controllable clutch on the axis shaft to engage and disengage said ratchet. 50
37. A manifolding platen comprising a rotatable platen member; an oscillatable housing adjacent to and independent of the platen member ends, said housings being connected by a longitudinal member through the platen member and upon which said platen member is independently rotatable; a rotatable shaft extending through the axis of the platen member; arms pivotally mounted about said axis shaft and extending 55
- radially through and playing in slots in the peripheries of the housings; a manifolding member carried by and between the outer ends of said arms; a rotatable counter shaft extending through one of said housings and into one end of the platen member and geared therein to rotate said platen member; coacting means between the axis shaft and the counter shaft to connect them for rotative engagement; and a cam on said counter shaft acting within an arcuate slot in the housing wall, to oscillate said housing. 60
38. A manifolding platen comprising a platen member; peripherally slotted housing members adjacent to and independent of the ends of the platen member; an axis shaft 65 common to said platen member and housing members; a laterally resilient arm in each housing member, the inner end of the arm being pivotally and radially slidably mounted about the common axis, said arm projecting through and playing in the peripheral slot of its housing member; means for directing the arms while executing their pivotal movement about the axis, into a path eccentric thereto; and a manifolding member carried by and between the outer ends 70 of the arms. 75
39. A manifolding platen comprising a platen member; a manifolding member; a pair of arms for carrying said manifolding member, pivotally mounted to swing about centers in a line passing longitudinally through the platen member; means operating through said platen member for swinging the arms in unison; means for effecting 80 a variable line-spacing movement of the platen member; means for effecting a definite line spacing movement of the platen member; and means for selectively operating either line spacing means. 85

In testimony whereof I have signed my name to this specification.

MALCOLM L. COSSITT.
